US0D1005684S

(12) **United States Design Patent** (10) **Patent No.:** **US D1,005,684 S**
(45) **Date of Patent:** **** Nov. 28, 2023**

(54) **FOLDABLE STORAGE CONTAINER**

(71) Applicant: **Wei-Cheng Wang**, Taipei (TW)

(72) Inventor: **Wei-Cheng Wang**, Taipei (TW)

(**) Term: **15 Years**

(21) Appl. No.: **29/808,614**

(22) Filed: **Sep. 21, 2021**

(51) **LOC (14) Cl.** **03-01**
(52) **U.S. Cl.**

USPC **D3/299**; D3/294; D9/418

(57) **CLAIM**

The ornamental design for a foldable storage container, as shown and described.

DESCRIPTION

FIG. 1 is a front perspective view of a foldable storage container showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a front perspective view thereof, showing the design for a foldable storage container with the front side in a partially open configuration; and,

FIG. 9 is a front perspective view thereof, showing the design for a foldable storage container with the top side in a partially open configuration.

1 Claim, 6 Drawing Sheets
